(57) **CLAIM**

The ornamental design for an x-ray analysis device, as shown and described.

DESCRIPTION

FIG. 1 is a front elevational view of an x-ray analysis device showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof, showing a front door being opened to a fully opened position;

FIG. 8 is a front elevational view showing a front door being opened to a middle position; and,

FIG. 9 is a front elevational view showing a front door being opened to a fully open position.
